CLAIM

The ornamental design for a reversible insert for a bird feeder, as shown and described.

DESCRIPTION

FIG. 1 is an isometric view of a reversible insert for a bird feeder showing our new design inserted in a first orientation into a bird feeder.

FIG. 2 is a perspective view of the reversible insert for a bird feeder.

FIG. 3 is a front view of the reversible insert for a bird feeder shown in the first orientation.

FIG. 4 is a front view of the reversible insert for a bird feeder shown in a second orientation.

FIG. 5 is a side view of the reversible insert for a bird feeder.

FIG. 6 is a top view of the reversible insert for a bird feeder; and,

FIG. 7 is a bottom view of the reversible insert for a bird feeder.

The broken lines shown in the Figures are environment only and form no part of the claimed design.

The shade lines in the Figures show contour and do not claim surface ornamentation or treatment.
